UNITED STATES PATENT OFFICE.

THOMAS M. KENNEY, OF CAMBRIDGE, MASSACHUSETTS, ASSIGNOR TO
FRANCIS EDGAR MASON, OF SAME PLACE.

PENCIL.

SPECIFICATION forming part of Letters Patent No. 295,923, dated April 1, 1884.

Application filed March 12, 1883. (No model.)

To all whom it may concern:

Be it known that I, THOMAS M. KENNEY, of Cambridge, county of Middlesex, State of Massachusetts, have invented an Improvement 5 in Pencils, of which the following description, in connection with the accompanying drawings, is a specification, like letters on the drawings representing like parts.

My invention relates to a pencil having a 10 movable lead, and has for its object to produce a simple, cheap, and effective mechanism for propelling the lead forward through the usual tip of the main body of the pencil. The lead-propelling device has a longitudinal 15 sliding movement relative to the body of the pencil and the lead-holding tube, and is provided with a series of shoulders or projections to engage the upper end of the lead and move it through the body and tip as the said propelling device is moved longitudinally in the 20 said pencil-body. The longitudinal movement of the propelling device, and consequently of the lead, is resisted by a friction device having sufficient holding-power to prevent 25 such longitudinal movement or slipping under the pressure ordinarily exerted between the end of the lead and paper in writing, although the said holding-power is overcome by a considerably stronger pressure brought to 30 bear on the feeding device or lead engaged thereby. The projections of the feeding device engage the upper end of the lead to move it forward or out through the tip of the pencil-body, and when the feeding device is withdrawn or moved toward the upper end of the 35 pencil-body the lead will remain held by the tip. The shoulders or projections of the feeding device are so arranged or spaced relatively to one another that when one has fed the lead forward as far as the longitudinal movement 40 of the feeding device will allow, and the feeding device is then withdrawn or moved back as far as possible, the lead meanwhile being held by the tip and not accompanying the feeding device in its backward movement, a 45 succeeding projection or shoulder will engage the said lead, so that the latter will then be fed forward from the point where it was left by the projection that previously acted upon it.

Figure 1 is a longitudinal section of a pencil embodying this invention; Fig. 2, an elevation of the feeding device and tip of the pencil; and Fig. 3, a transverse section on line *xx*, Fig. 1.

The main body of the pencil comprises a 55 tube, *a*, of suitable or usual material, such as hard rubber, provided at one end with a tip, *b*, shown as of metal split at its end, as shown at 2, to cause it to hold the lead *c* with moderate friction, the said lead passing through a 60 tube, *d*, connected at its lower end with the said lead-holding tip *b*, and having a longitudinal slot, as shown at 3, for the greater portion of its length. The parts *a b d* constitute the body or fixed portion of the pencil, 65 they having no movement with relation to one another, and in speaking of the movement of the lead and its propelling mechanism relative to the said body the term "forward" or "downward" will be applied to movement 70 toward the tip *b*, and "backward" or "upward" to movement in the reverse direction.

The propelling device *e* is made tubular for a short distance from its upper end, it surrounding or inclosing the upper end of the 75 lead-holding tube *d*, and being itself inclosed by the tube *a*, and adapted to slide or move longitudinally within the space between the said tubes *d* and *a*. The said feeding device *e*, the whole or a portion of which will preferably be struck up from sheet metal, and may be tubular for its entire length inclosing the tube *d*, or may be merely a strip overlying the slot of the said tube, is provided with 80 a series of lead-feeding projections, *f*, (shown 85 as mounted upon the ends of spring-arms *i*,) the said projections *f* being normally pressed inward by the spring-arms through the slot 3 of the tube *d* in position to engage the end of, the lead *c* thereon, the said arms *i* yielding 90 sufficiently to permit the lead to be pushed through the tube *d* from the upper end thereof, and resting on the side of the said lead, as shown in Fig. 1, until its end is moved past them. The feeding device *e* is provided with 95 a holding device or friction-clamp, *m*, shown in this instance as a split tubular portion of the feeding device *e*, surrounding the lower

end of the tube *d*, and pressing against the said tube by its elasticity with sufficient force to afford considerable resistance to the longitudinal movement of the lead-propelling device *e* in the pencil-body *a* in either direction. The downward movement of the lead-propelling device is limited by its end coming in contact with the shoulder *5* in the tip *b*, and its upward movement is limited by a stop 10 projection, *n*, shown in this instance as connected with the tube *d*. The upper end of the feeding device *e* is threaded, as shown at *e'*, to receive a cap or knob, *o*, provided with a plunger, *p*, adapted to enter the upper end of the 15 lead-receiving tube *d*, the lower end, *f'*, of which forms a shoulder, which first acts on the lead *c* when a new lead of full length is employed in the pencil.

In operation, when it is desired to provide 20 a pencil with a new lead, the cap *o*, with its connected plunger *p*, is unscrewed from the upper end of the propelling device *e*, which should be at that time withdrawn to its uppermost position, as shown in Fig. 1, and the 25 lead is then pushed down through the tube *d* from the upper end toward the tip *b*, it pressing the projections or fingers *f* aside as it passes through the said tube. The cap *o* is then applied, the plunger *p* pressing the lead farther 30 down until, when the cap is wholly screwed on, the lead of full length will just enter or project through the tip *b*, after which, as the lead wears away, or if the user desires the lead to project a considerable distance, the 35 knob *o* is forced downward with relation to the body *a* with sufficient power to overcome the friction of the clamp *m*, moving the feeding device, and through the shoulder *f'* also moving the lead *c* forward until its point projects the desired distance.

When it is desired to have the point of the lead within the tip and body of the pencil, as for carrying the pencil in the pocket, the point of the lead may be forcibly pressed inward toward the body *a*, thus pushing the lead and feeding device both backward until the end of the lead is wholly inclosed within the tip *b*, or until the stop *n* operates to arrest the backward movement of the propelling mechanism 45 and lead. As the lead gradually wears away, the feeding mechanism will have to assume a lower and lower position when the lead is in use, and at last the end of the plunger *p* or shoulder *f'*, when the feeding mechanism is in its extreme forward position, will not cause 50 the lead to project a sufficient distance beyond the tip. When this point is arrived at, the propelling mechanism is withdrawn by means of the knob *o* from the body *a* of the pencil, 55 the end of the lead then being held by the tip *b*, and not accompanying the propelling device 60 in its upward movement, so that when the latter is withdrawn as far as the stop *n* permits the next feeding projection *f* below the end *f'* 65 of the plunger will engage the lead, as shown

in Fig. 1, and the latter will be fed forward until another length equal to the length of movement of the feeding device has been used up or worn out. After this, the next lower projection, *f*, will engage and feed the lead, and 70 then the next, and the lowest one of the said projections feeds the lead almost to the end of the tip, so that only a very small portion will remain unused. The space between the feeding projections *f* is somewhat less than the 75 length of the feeding movement limited by the tip and the stop *n*, so that each one will act with certainty to feed the lead far enough to be engaged by the next one.

It is obvious that the construction can be 80 modified in some particulars without departing from the invention—as, for instance, the friction may be between the outside of the feeding device and the inside of the tip *b* or tube *a*, instead of between the inside of the 85 said feeding device and the outside of the tube *d*, which latter may be wholly omitted, in which case the feeding device will be made tubular for its entire length, to properly hold the lead.

The stop *n* might be attached to the inside 90 of the tip *b*, or might be made as a lip or flange upon the upper end of the tube *a*, to engage the shoulder or collar upon the feeding device. If desired, a plunger or follower might be placed 95 at the upper end of the lead and engaged by the feeding device, instead of having the latter operate directly upon the lead.

I claim—

1. In a pencil, the combination, with the 100 pencil-body, of a lead-feeding device longitudinally movable in the said body, having a series of projections or shoulders to successively operate upon the lead, and the holding device, resisting without positively preventing the 105 longitudinal movement in either direction of the said feeding device and lead under moderate pressure, substantially as described.

2. The pencil-body having a lead-holding tip, combined with the longitudinally-movable 110 lead-feeding device, having a series of yielding projections or shoulders to successively operate upon the lead, and a frictional clamp to resist and stops to positively limit the longitudinal movement in either direction of the 115 propelling device relative to the pencil-body, substantially as described.

3. The pencil-body consisting of an outer tube, a split lead-holding tip, and inner lead-receiving tube slotted longitudinally, all fixed 120 with relation to one another, combined with the longitudinally-movable and frictionally-held feeding device, having a knob outside the end of the said outer tube, and a series of yielding lead-feeding projections or shoulders normally pressed into the said slot, substantially 125 as described.

4. The combination of the pencil-body with a longitudinally-movable lead-feeding device having a series of projections or shoulders, 130

and its removable cap or knob provided with a plunger, substantially as described.

5. The body consisting of the tubes *a* and *d* and tip *b*, combined with the feeding device having a series of projections, *f*, and a clamp or friction device, *m*, substantially as described.

In testimony whereof I have signed my name to this specification in the presence of two subscribing witnesses.

THOS. M. KENNEY.
